UNITED STATES PATENT OFFICE.

FLORENCE L. GRANT AND CARL A. BROWN, OF FOSTORIA, OHIO, ASSIGNEES TO
GENERAL ELECTRIC COMPANY, A CORPORATION OF NEW YORK.

DESIGN FOR A LAMP SHADE OR REFLECTOR.

45,625.

Specification for Design.

Patented Apr. 21, 1914.

Application filed April 21, 1913. Serial No. 762,741. Term of patent 14 years.

To all whom it may concern:

Be it known that we, FLORENCE L. GRANT and CARL A. BROWN, citizens of the United States, residing at Fostoria, in the county of Seneca and State of Ohio, have invented a new, original, and ornamental Design for Lamp Shades or Reflectors, of which the following is a specification, reference being had to the accompanying drawing, forming part thereof.

The figure is an elevation of a reflector

substantially circular in plan showing our new design.

We claim—

The ornamental design for a lamp shade or reflector as shown.

FLORENCE L. GRANT.
CARL A. BROWN.
